UNITED STATES PATENT OFFICE.

FREDERICK SCHILLING, OF NEWARK, NEW JERSEY.

FOLDABLE UMBRELLA.

1,276,971.

Specification of Letters Patent. Patented Aug. 27, 1918.

Application filed June 20, 1916. Serial No. 104,708.

To all whom it may concern:

Be it known that I, FREDERICK SCHILLING, a citizen of the United States, and a resident of Newark, county of Essex, and State of New Jersey, have invented a certain new and useful Improvement in Foldable Umbrellas, of which the following is a full, clear, and exact specification.

This invention relates more particularly to a class of umbrellas, and has for its object primarily to provide a form of umbrella adapted when not in use to be folded into a compact parcel for occupying a limited space so as to be readily carried in a hand satchel, or trunk or otherwise for convenient use when traveling. This is accomplished mainly by providing a rod, and to the rod is pivoted one of the corresponding ends of a number of ribs for being swung 20 radially to and from the rod. Each of the pivoted ribs has a section which is slidably adjustable thereon whereby the ribs may be reduced and increased in length, and on the rod is a movable sleeve to which is pivoted one of the corresponding ends of a plurality of stays each having its other end pivotally held to the adjustable section of each of the ribs so that when the umbrella is closed the sleeve and the stays may be 30 moved for guiding the adjustable sections of the ribs to reduce the lengths of the ribs.

Other objects of the invention are to provide retaining elements for releasably holding the adjustable sections of the ribs with the stays against accidental movement when the sections are extensibly adjusted on the pivoted sections of the ribs; to provide forms of the rod which may be composed of detachably connected sections so as to be collapsible when the umbrella is not in use; and to provide a ring adapted to be removably guided over the stays when closed on the rod for allowing the stays with the sleeve to be moved for slidably adjusting 45 the adjustable sections of the ribs on the pivoted sections.

A practical embodiment of the invention is represented in the accompanying drawing forming a part of this specification in which similar characters of reference indicate corresponding parts in all the views, the said invention being more fully described herein-after, and then pointed out in the claims at the end of the description.

In the drawing, Figure 1 is a fragmentary

sectional view taken through part of a foldable umbrella embodying my invention.

Fig. 2 is an enlarged inverted plan, partly broken away, of one of the extensible ribs used in the umbrella. 60

Fig. 3 is an enlarged fragmentary view, partly in section and partly in detail, taken on the line III—III of Fig. 1, and

Fig. 4 is a view showing the ribs of the umbrella when folded as well as showing 65 the parts of the rod of the umbrella when separated.

The umbrella has a rod 10 which may be of a collapsible form composed of a main section 11, an end section 12, and a handle 70 section 13, and these sections of the rod may be detachably connected in any suitable manner, though I prefer to provide the sections in the forms of metal tubes. In the main tubular section 11 of the rod 10 is a 75 core, or bar 14 of a length so that both of its ends extend some distance beyond the ends of this tubular section, and these protruding ends are threaded, as at 15 and 16. The bar 14 is of less diameter than the tubular 80 section 11, and this bar is rigidly held centrally of the tubular section by one, or more pins 17 being driven through the tubular section and through the bar to provide a space 18 between the bar and the tubular 85 section. In the end section 12 of the rod 10 is arranged a tube 19 so that one of its ends protrude from one end of the end section, and this tube is tightly held in the end section by a pin 20 passed through the openings in the tube and in the end section. The protruding end of the tube 19 is of a diameter to removably fit in the space 18 between the bar 14 and the main section 11, and this protruding end of the tube is 90 inferiorly threaded for allowing the threaded end 16 of the bar 14 to be screwed therein for detachably connecting the end section 12 to the main section 11. In the end of the handle section 13 is a tube 21 with one 95 of its ends protruding out of the handle section, and this tube is secured in the handle section by means of a pin 22 driven through openings in the handle section and in the tube. The tube 21 is of a diameter 100 so as to removably fit in the space 18 between the bar 14 and the main section 11, and the interior of the protruding end of the tube 21 is threaded, as shown, to permit the threaded end 16 of the bar to be screwed 110

therein for also removably fastening the handle section to the main section. Instead of employing this form of collapsible rod, I may use a rigid rod if desired.

- 5 At the end of the main section 11 of the rod adjacent to the end section 12 is a stationary ring 23 of the usual type having radially extending spaced lugs, and on this main section contiguous to the ring 23 is a 10 spring catch, or stop, as 24, which may be of a form used in ordinary umbrellas. In the spaces between the lugs of the ring 23 are pivoted one of the corresponding ends of a number of ribs, as 25, all of which are 15 preferably similar in formations. Each of the ribs 25 is of a tubular form as well as being somewhat similar to the length of the main section 11 of the rod 10, and all of these ribs are arranged so as to be swung 20 radially to and from the rod. In the underside of the tubular section of each of the ribs 25, and disposed lengthwise thereof, is a slot 26 extending from the pivoted end of the rib to nearly its opposite free end. 25 Part of the slot 26 of each of the ribs is reduced in width, as at 27, by forming the adjacent portions of the wall of the rib accordingly. In the slotted tubular section of each of the ribs is a slidable section 28 30 preferably in the form of a rod and by each rib being made in this manner all of the ribs are adapted to be increased and reduced in lengths by the rods being movable inwardly and outwardly of the free ends 35 of the tubular sections. Connected to the slidable section 28 of each rib as well as being fastened on the rod 10 above the ring 23 is a cover 30. The cover 30 is thereby arranged on top of the ribs. 40 On the rod 10 is a slide, or sleeve 29 which may be of a well known, or any preferred type adapted to be moved back and forth on the rod, and this slide has a slot, or opening 30 for reception of the 45 spring stop 24 when the slide is moved accordingly on the rod and this slide has outwardly extending spaced lugs 31. In the spaces between the lugs of the slide 29 are pivoted one of the corresponding ends of a 50 number of stays 32 which are of similar numbers to the ribs, and serving to releasably hold the slidable sections 28 against accidental movement in the tubular sections of the ribs, I provide a plurality of retaining elements, as 33, all of which may be of 55 similar formations.
- Each of the retaining elements 33 is preferably made of spring metal bent in substantially a U-shape to provide two spaced arms 60 34 and 35, and through these arms contiguous to their free ends are registered slots 36 and 37. The connected end of the slotted arms 34 and 35 of each of the retaining elements 33 is soldered, or otherwise secured to 65 the end of each of the slidable sections 28 of the ribs which are disposed in the tubular sections thereof, while between the arms of each of the retaining elements is pivoted the second end of each of the stays 32 by means of a pin which is movably disposed through 70 the slots of the arms of its respective retaining element. The spring arms 34 and 35 of each of the retaining elements are spaced apart at a distance to move freely in the slots 26 of the tubular sections of the ribs as 75 well as being spaced apart at a distance so that when the retaining elements are guided into the reduced end portions 27 of the slots the tension of the arms will cause them to frictionally engage the edge of the reduced 80 portions of the slots, and the slidable sections of the ribs will then be releasably held in the tubular sections thereof against accidental displacement when the slidable sections are extensibly adjusted in the tubular 85 sections.
- In practice the umbrella is opened for use by moving the slide 29 on the rod 10 toward the end section 12 of the rod so that the spring stop 24 will be seated in the slot 30 90 of the slide. The stays 32 will then be guided radially outward from the rod, and the slidable sections 28 of the ribs will be moved also outwardly of the tubular sections 25, simultaneously with the radial 95 movement of the ribs in the manner common to the raising of umbrellas of the usual types. When the stays 32 have been swung sufficient distances the retaining elements 33 will be admitted into the reduced end portions 27 of the slots 26 for releasably holding the sections 28 of the ribs against accidental movement, as above explained, and to fold the umbrella so as to be carried in a hand satchel, or trunk, or otherwise for 100 convenient transportation, the slide 29 is released from its engagement with the stop 24 by springing the stop from its engagement in the opening of the slide 29. The slide is then reversely guided on the rod 105 toward the handle section 13, and the stays 32 with the ribs will thereby be reversely swung to closed positions on the rod. To permit the umbrella to be folded, or reduced in length, a ring, as 36, or other suitable means is guided over the ribs 25, and the sleeve, or slide 29 with the stays are forced toward the top, or end section 12 of the rod 10. The sections 28 of the ribs will thereby be slidably adjusted inward of the 110 tubular sections 25, and the cover 30 will be partially infolded between the tubular sections 25 of the ribs and the stays 32. The end section 12 of the rod 10 may then be disconnected from the main section 11 by 115 unscrewing the tube 19 from the bar 14, and the handle section 13 may also be detached from the main section of the rod by unscrewing the tube 21 also from the bar 14 of the main section of the rod. In this manner 120
- 125
- 130

ner a simple and efficient umbrella may be provided for being packed into a very limited space when not in use.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

The combination, in a foldable umbrella, of a rod composed of detachable sections, a plurality of ribs each having one end pivoted to the rod for being swung toward and from the rod, and each of the ribs having

a slotted tubular section with a slidably adjustable rod in the tubular section of its respective rib whereby the ribs may be reduced and increased in length, a sleeve on 25 the sectional rod, a plurality of stays each having one end pivoted to the sleeve, a plurality of yielding retaining elements one pivotally connecting the second end of each stay to the slidable rod of each of the ribs, 30 and the retaining elements being adapted to frictionally engage the tubular sections of the ribs to hold the adjustable rod against accidental movement when extensibly adjusted in the pivoted sections. 35

This specification signed and witnessed this 17th day of June A. D. 1916.

FREDERICK SCHILLING.
